UNITED STATES PATENT OFFICE.

EMMETT M. KEY, OF TULSA, OKLAHOMA.

NOTCHING DEVICE.

1,387,851.

Specification of Letters Patent. Patented Aug. 16, 1921.

Application filed January 23, 1918. Serial No. 213,406.

To all whom it may concern:

Be it known that I, EMMETT M. KEY, a citizen of the United States, residing at Tulsa, in the county of Tulsa and State of Oklahoma, have invented certain new and useful Improvements in Notching Devices, of which the following is a specification.

This invention relates to notching devices and has for its object the production of an efficient notching device which will permit an operator to conveniently cut notches in the ceiling joists of a building for receiving electric conduit pipes, gas pipes, or water pipes, while standing upon the floor of a building.

Another object of this invention is the production of an efficient notching device which will efficiently grip the joist of a building, and permit the cutting saw to cut into the under face of the joist.

With these and other objects in view, this invention consists of certain novel constructions, combinations, and arrangements of parts as will be hereinafter fully described and claimed.

In the drawings:

Figure 1 is a side elevation of the notching device,

Fig. 2 is an edge elevation of the notching device,

Fig. 3 is a side elevation of the upper end of the notching device, the joist gripping jaws being shown drawn close together,

Fig. 4 is a top plan view of the notching device,

Fig. 5 is a longitudinal sectional view through the notching frame,

Fig. 6 is an enlarged top plan view of one end of the notching frame,

Fig. 7 is an enlarged longitudinal sectional view through the notching frame taken on line 7-7 of Fig. 5,

Fig. 8 is a section taken on line 8-8 of Fig. 3, the saw being eliminated therefrom,

Fig. 9 is a detail fragmentary perspective view of one of the spring pressed shoes adapted to support the notching frame,

Fig. 10 is a section taken on line 10-10 of Fig. 1,

Fig. 11 is a vertical central section through the ejector table showing the ejector arms connected thereto,

Fig. 12 is a vertical section through one of the ejector arms,

Fig. 13 is a perspective view of one of

the gripping jaws, the supporting link arms being broken away,

Fig. 14 is a transverse sectional view through one end of the saw carrying frame, showing the worm screw and gear co-operating with the adjusting plate for shifting the saw blades, and

Fig. 15 is a side elevation of one end of the saw carrying frame, showing a slot formed in the adjusting plate, within which works the lower end of the pin carrying the saw engaging hinges.

By referring to the drawings, it will be seen that 1 designates the supporting standard, which carries a head 2 at its upper end. This head 2 is bifurcated at its upper end and the link arms 3 are pivotally mounted within the bifurcated portion of the head 2, upon a pivot pin 4. Each link arm 3, is provided with a laterally extending portion 5 which terminates in an upwardly inclined end 6. Each link arm 3 is also provided with a downwardly inclined body portion 7, which body portion is provided with a longitudinally extending slot 8. The slot 8 in each link arm 3 extends at an angle of approximately 45° to the vertical axis of the link arm 3 and each link arm 3 is also provided with a projecting ear 8' which extends at right angles to the longitudinal axis of the body portion 7.

The link arms 3 are placed in crossed relation as shown in Fig. 5 and a pin 9 passes through the slots 8 of the link arms 3, and through the guide slots 10 formed in the head 2. This pin 9 is carried by an operating rod 11 which operating rod 11 passes longitudinally through the standard 1. The rod 11 is secured at its lower end to the pin 12, the pin 12 passing through the slot 13 formed near the lower end of the standard 1, and the arc-shaped slot 14 formed in the operating handle 15, and working in said slots. The handle 15 is pivotally secured to said standard off center thereby causing the slot 14 to act as an eccentric channel as the handle 15 is swung and consequently moving the rod 11 longitudinally of the standard as the handle 15 is thus swung.

Joist gripping jaws 18 are carried by the link arms 3, and are provided with vertically extending alined slots 19 through which pass the securing pins 20. These pins 20 are carried by the inclined ends 6 and the projecting ears 8'. By having the

link arms 3 arranged in crossed relation, it will be seen that a toggle arrangement is provided due to the fact that the ends 6 of one link arm and the ear 8' of the adjoining 5 link arm are connected to the same gripping jaw 18. Each jaw 18 is provided with a gripping tooth 22, which is adapted to bite into the joist and firmly hold the notching device in engagement therewith.

10 A casing 23 is secured to the rear of each gripping jaw 18 and this casing is provided with a rolled portion 25 at each end thereof, this rolled portion 25 fitting within the notched or cut-away portion 24'. Pins 24 15 extend through these rolled portions 25 as shown clearly in Fig. 5 of the drawings and in this way firmly anchor the casings 23 in engagement with the gripping jaws 18. Springs 26 are carried within the lower ends 20 of the casings 23 as shown clearly in Fig. 5 of the drawings, and these springs 26 support the lugs 27, these lugs 27 projecting out flush with the sides of the casings 23 and being capable of moving upwardly and 25 downwardly within the casings to permit the saw carrying frame to be adjusted relative to the gripping jaws 18.

The saw carrying frame 29 is provided with a top plate 30 and a bottom plate 31 30 upon each side thereof which are secured together by means of side ribs 32. The opposite plates 30 and 31 are spaced to provide a slot 34, through which the gripping jaws 18 pass, for engaging a joist upon which 35 the notching device is adapted to operate.

The upper and lower plates 30 and 31 project inwardly from the side ribs 32 as shown clearly in Fig. 8 of the drawings for producing tracks upon which the shoulder portions 28 of the lugs 27 are adapted to slide.

40 A pair of parallel arms 35 are secured to the shoulder portions 28 of each lug 27 and these lugs are adapted to travel within the tracks formed by the plates 30 and 31 45 as shown in Fig. 8 and as previously explained.

The arms 35 projecting from the lugs 27 of one gripping jaw 18 overlap the arms 35 of the lugs 27 of the opposite gripping jaw 18 as shown in Fig. 5 thereby allowing the gripping jaws 18 to be freely moved toward or away from each other by the operation of the handle 15.

50 Pintle pins 36 and 36' are carried in the ends of the frame 29 and a hinge 37 is mounted upon each of the pintle pins 36 and 36'. A saw blade connecting hinge 38 is connected to each of the leaf-portions 39 of the hinges 37 and each of these saw 55 blade connecting hinges 38 carries a pintle pin 40 as shown clearly in Figs. 4 and 6 of the drawings. A saw blade 41 is connected to the respective saw carrying hinges 38, which are mounted near the ends of the 60 frame 29, thereby holding the saw blades 41 65

in parallel relation in the manner shown in Fig. 4 of the drawings.

A gage plate 42 is carried by the top face of the frame 29 and rests upon the top plates 30 and this gage plate 42 as shown in detail in Fig. 6 is provided with diverging 70 slots 43 formed in the respective ends of the plate 42. The pintle pins 40 which carry the hinges 38 extend down into these slots 43 as indicated in Fig. 5 of the drawings. 75 The plate 42 is provided with a notch 44 at one end thereof as shown in the drawings at the right end of Fig. 5 into which notch 44 extends pin or bolt 36 for constituting a guide for the plate 42. The plate 42 is of course provided with an enlarged aperture 45 extending through the plate and this enlarged aperture 45 communicates with a narrow slot 46, through which slot 46 passes the pin or bolt 36' carried by one end of the 80 frame 29, the slot 46 being located at the opposite end of the plate 42 to the notch 44.

A worm screw 47 is placed within a socket 48 formed in the frame 29 and is held therein by means of a face plate 49, which plate 90 49 is detachably held in engagement with the frame 29 by means of the screws 50. The worm screw 47 meshes with a worm gear 51 formed upon the under face of the plate 42 and it will be seen by considering Figs. 5, 95 6 and 14 that the plate 42 may be shifted longitudinally of the frame 29 by the rotation of the worm screw 47 within the socket 48.

As the worm screw 47 is rotated for shifting the plate 42 the saw blades 41 will be moved apart laterally or drawn together according to the direction of rotation of the worm screw 47. This movement of the saw blades 41 will be caused by the working of 100 the lower ends of the pins 40 within the slots 43 formed in the respective ends of the plate 42. The saw blades 41 may in this manner be adjusted to cut notches of suitable widths in the lower edges of a ceiling joist and the 110 like.

A saw frame shifting arm 52 is pivotally mounted upon the head 2 at 2' and is provided with a longitudinally extending slot 53 through which slot 53 passes a bolt 54, 115 carried by the frame 29 and is adapted to permit the frame 29 to be reciprocated transversely of the gripping jaws 18 as the shifting arm 52 is swung upon its pivot 2'. A suitable handle 55 is secured to the link 52 120 for the purpose of swinging the same. The opposite side of the frame 29 is also engaged by means of a link 56 which link is supported at its lower end upon a pivot bolt 57.

When it is desired to operate the notching 125 device, the standard 1 is raised to a vertical position and the edges of the saw blades 41 are extended transversely across the lower edge of a joist. The standard 1 is then forced upwardly for causing the gripping 130

jaws 18 to extend above the upper edges of the saw blades 41 and above the lower edge of the joist and be in a position to efficiently grip the joist above the upper edges of the saw blades. After the gripping jaws 18 have been raised to a sufficient distance above the upper edges of the blades 41, the operating handle 15 is swung downwardly, thereby causing the pin 9 to travel downwardly 5 through the slots 8 formed in the link arms 3, as shown clearly in Fig. 5 of the drawings. The biting teeth 22 of the gripping jaws 18 will consequently be forced toward each other and will efficiently bite or dig into the joist and thereby efficiently and rigidly support or suspend the notching devices upon the joist in a position ready for operation. After the notching device has been firmly secured to the joist, the saw blades 41 may be 10 reciprocated across the lower edge of the joist for cutting the same, this reciprocating movement being accomplished through the swinging of the handle 55. The springs 26 carried within the frames 23 will yieldably force the saw blades 41 into firm engagement with the joist by forcing upwardly upon the lugs 27 and thereby permit the blades 41 to efficiently cut into the joist. 15

From the foregoing description, it will be seen that a very simple and efficient device has been produced for cutting notches in the lower edge of a ceiling joist, whereby the operator may stand upon the floor of the building and conveniently operate the notching device for the purpose of forming the desired notches in the joist. 20

It should be understood that certain obvious detail mechanical changes may be made in the present device without departing from the spirit of the invention, so long as these changes fall within the scope of the appended claims. 25

An ejector is provided for use in connection with the present invention for facilitating the ejection of the block or chunk from between the jaws 18 after the joist has been cut by means of the saw blades 41, and this ejector comprises an ejector table 58 which is supported upon the telescoping 30 arms or tubes 60, each telescoping arm or tube 60 comprising an upper hollow tubular section within which works the lower rod section 61, these rod sections 61 engaging the springs 62 mounted within the tubular 35 upper sections of the arms 60. These springs 62 are adapted to normally urge the table 58 upwardly. The table 58 is adapted to engage the lower edge of the joist and extend between the saw blades 41. After the joist 40 has been cut to the desired depth, and it is desired to release or remove the block of wood which remains between the saw blades, this block or chunk of wood may be broken away from the joist by swinging the handle 45 1 from side to side upon the joist, the table

58 constituting a fulcrum or pivot pin for the notching device while the handle 1 is swung from side to side. As the handle 1 is swung from side to side, the block or chunk of wood between the blades 41 will 70 be broken loose on a line parallel with the teeth 22 whereupon the notching device will drop through force of gravity away from the joist. The block of wood, at this time is held between the teeth 22 and the ejector 75 table 58. After the handle 15 is raised for the purpose of spreading the gripping arms 18 apart, the springs 62 however will force the chunk of wood or block engaged by the table 58 out from between the jaws 18 thereby 80 freeing the notching device from the block which has been cut. The arms 60 are pivotally secured to the depending flanges 59 of the table 58 as shown in Fig. 5 of the drawings, and at their lower ends to the link 85 arms 3 by means of pins 63. It is of course understood that the present device may be employed for cutting notches in the top of the joist in the same manner as described above, merely by reversing the position of 90 the notching device and causing the saws 41 to hang below the standard 1.

What is claimed is:—

1. A notching device of the class described comprising a saw carrying frame, said saw carrying frame provided with track grooves formed therein, gripping jaws carried by said frame, lugs slidably mounted upon said gripping jaws, means formed upon said lugs and working within said track grooves 95 for constituting a guide for said jaws, and means for yieldably supporting said lugs. 100

2. A notching device of the class described comprising a saw carrying frame, said saw carrying frame provided with track grooves 105 formed therein, gripping jaws carried by said frame, lugs slidably mounted upon said gripping jaws, springs engaging said lugs, means formed upon said lugs and a casing carried by each gripping jaw and constituting 110 a support for said springs and lugs carried by said jaws.

3. A notching device of the class described, comprising a saw carrying frame, gripping jaws extending through said saw carrying frame, said gripping jaws provided with vertically extending slots, operating links pivotally connected together and interposed between said gripping jaws, each link provided with pins working in said slots, each 115 link being connected at its respective ends to the opposite jaws, and means for swinging said links and causing said jaws to move with respect to each other. 120

4. A notching device of the class described 125 comprising a saw carrying frame, a plurality of gripping jaws extending through said saw carrying frame, said saw carrying frame provided with track ways, formed therein, a supporting lug carried by each jaw, yield- 130

able means supporting said lugs, each lug provided with inwardly projecting arms, the arms of one lug overlapping the arms of the opposite lug, and said arms working 5 within said track ways, for constituting a guide for said gripping jaws.

5. A notching device of the class described comprising a saw carrying frame, a pivot screw supported upon each end of said saw 10 carrying frame, hinges carried by said pivot screw, and saw blades, carried by said hinges.

6. A notching device of the class described comprising a saw carrying frame, a support 15 for said frame, a pivot screw supported upon each end of said saw carrying frame, hinges carried by said pivot screw, saw blades carried by said hinges, means for adjusting said saw blades with respect to each other, and 20 means for reciprocating said saw carrying frame upon said support.

7. A notching device of the class described comprising a saw carrying frame, supporting means for said frame, pivot pins carried by said saw carrying frame, a gage 25 plate mounted upon said saw carrying frame, a hinge mounted upon each pivot pin, saw blades carried by said hinges, means for moving said gage plate upon said supporting frame, and means carried by said saw 30 blades and engaging said gage plate for shifting said saw blades with respect to each other as said gage plate is moved longitudinally upon said saw carrying frame.

35. 8. A notching device of the class described comprising a saw carrying frame, supporting means for said saw carrying frame, a plurality of saw blades carried by said frame, a gage plate carried by said frame, and engaging said saw blades for shifting the 40 same laterally as said plate is moved longitudinally upon said saw carrying frame, a worm gear formed upon the under face of said gage plate, and a worm screw engaging 45 said worm gear for shifting said gage plate upon said saw carrying frame.

9. A notching device of the class described comprising a saw carrying frame, supporting means for said saw carrying

frame, a plurality of saw blades carried 50 by said frame, a gage plate carried by said frame, and engaging said saw blades for shifting the same laterally as said plate is moved longitudinally upon said saw carrying frame, a worm gear formed upon the 55 under face of said gage plate, said gage plate provided with diverging slots arranged near each end thereof, and pins carried by said saw blades and working in said slots, for shifting said saw blades as said plate is 60 moved longitudinally.

10. A notching device comprising a saw carrying frame, supporting means therefor, parallel saws carried by said saw carrying frame for cutting a block from the work upon 65 which the device is supported, and a block ejecting means carried by said carrying frame.

11. A notching device comprising a frame, 70 saws carried thereby and adapted to cut a block from the work upon which said device is operated, an ejector table, and spring pressed means for actuating said ejector table for ejecting a block from between said saws after said notching device has dropped 75 out of engagement with the work.

12. A notching device comprising a frame, 80 saws carried thereby, joist gripping means carried by said frame, said saws adapted to cut a block from said joist, an ejector table interposed between said saws, spring pressed plungers engaging said table and adapted to eject a block from between said saws as said notching device drops from engagement with the work, and means connecting said plunger with said joist gripping means for spreading said joist gripping means apart. 85

13. A notching device of the class described comprising a frame, a plurality of 90 saws carried thereby, and means located intermediate said saws for engaging the work and supporting the saws theron.

In testimony whereof I affix my signature in presence of two witnesses.

EMMETT M. KEY.
